VIBRATORY ELECTRIC MOTOR APPARATUS

John A. Hanley, Noroton, Conn., assignor to Gillette Safety Razor Company, Boston, Mass., a corporation of Delaware

Application January 31, 1940, Serial No. 316,498

16 Claims. (CL 172—126)

While the present invention is shown incorporated in an electric shaver, it is applicable also for a variety of other apparatus, such as hair clippers, massaging devices and the like, and the vibratory motor incorporated therein is of more general utility.

Among the objects of the invention are to provide a rugged electric motor structure of low cost, which shall have a minimum number of parts that can be assembled easily and economically without resort to pivot screws, pins or other small fastening or hinging parts that are apt to wear and cause looseness or jamming.

Another object is to provide a motor for a structure of the above type, which even under adverse conditions of operation is proof during use against electric shock to the user when the metal tool head is applied to the body.

Another object is to provide a vibratory motor for a device of the above type, in which magnetic leakage is kept at a minimum throughout the stroke, with consequent relatively high power and efficiency.

Certain features of the invention claimed herein both severally and in combination are the vibratory motor the floating armature of which is resiliently biased away from the field structure, with respect to which it has direct thrust rocking bearing engagement at its rear end, and the operating arm of which protrudes through the forward end of the insulating motor casing and is joined to the armature by an insulating molded coupling which rigidly connects said parts into electrically insulated relation, with respect to each other and in which a buffer structure near the forward part of the casing resiliently yields to the operating movement of the operating arm.

This application is for an improvement upon the invention of my copending application, Serial No. 149,055, filed June 19, 1937.

In the accompanying drawings in which is shown one of various possible embodiments of the several features of the invention,

Fig. 1 is a plan view of the shaving unit with the cover removed.

Fig. 2 is a view in longitudinal section taken on line 2—2 of Fig. 1.

Figs. 3 and 4 are transverse sectional views on the lines 3—3 and 4—4 respectively of Fig. 1.

Fig. 5 is a side elevation of the armature with parts broken away.

Fig. 6 is a bottom plan view of said armature.

Fig. 7 is a detail sectional view taken on line 7—7 of Fig. 5, and

Fig. 8 is an exploded perspective view showing the buffer assembly.

Referring now to the drawings, there is shown an insulating handle casing 10 for an electric shaver having at the forward end thereof the operating tool, in the form of a shaving head, illustratively shown as a rigid carrier block 11 having mounted therein a reciprocating cutter block 12 with teeth 13 overlapped by the inturned teeth 14 of the carrier block 11. The shaving head unit is removably affixed to the casing by means of a set screw 15. The shearing head shown may be replaced by any of numerous possible constructions of shearing heads or other tools that may be operated from the motor described hereinafter. From the rear end of the casing extends the electric cord set 16 the outer end of which (not shown), is plugged into an outlet box.

Within the casing is the electric motor which in the embodiment shown, comprises a stator which constitutes a laminated field structure F carried by insulating bosses 17 integral with the casing to which it is secured by bolts 18 threaded into nuts 19 that are molded into said bosses. The field structure is generally U-shaped, and desirably has a base 20 and legs 21 and 22 for end to end correlation with corresponding legs 23 and 24 unitary with the base 25 of the generally U-shaped laminated armature structure A.

The armature has a direct thrust bearing relation with the field structure. To this end the armature laminations are desirably conformed with registering triangular teeth 26 forming a ridge in the assembled armature structure, the sharp edge of which is lodged in the corresponding sharp trough of a notch 27 formed in the field structure leg at the rear end of casing 10. Notch 27 is of less height but of greater angularity than ridge 26 thereby to space the armature from the field structure by an air gap 28 therebetween with engagement only at the pivot edge to permit the desired rocking movement of the armature, with minimum of friction.

The ends of the other legs 22 and 24 near the forward end of casing 10, have obliquely cut ends 22' and 24' to determine an air gap 33 therebetween, which desirably extends at an angle of 45 degrees to the length of the legs, for a purpose which will appear more fully hereinafter.

The armature is resiliently held to permanently maintain the thrust bearing engagement set forth. For this purpose, the armature and field laminations may be provided with unitary anchoring lugs or projections 30 at their rear ends, about which are hooked the inturned ends 31

of a leaf spring 32, which is thereby effectively mounted to bias the armature about its thrust bearing mount 26, 27 away from the field structure to open the air gap 33.

Preferably the motor includes two electro-magnet coils 34 and 35 desirably connected in series at 37 encircling the respective legs of the field and armature assembly, so that the respective air gaps 28 and 33 are contained within the respective coils. To prevent possible shifting of coil 35 in the vibratory movement of the armature, said coil is desirably affixed to the field structure F by a brass clip 36 extending transversely thereabout and held in place at toe 36' by the bolt 18.

The vibratory movement of the armature is imposed upon the cutter block 12 through the metal operating arm 38, which is offset from the armature proper, and is rigidly connected thereto, to form a unitary part of the armature structure. Operating arm 38 protrudes through a longitudinal port 39 in the casing 10 for engagement of the reciprocating cutter 12.

According to the invention, the operating arm 38 is electrically insulated with respect to the motor. For this purpose, the armature is provided with a protruding mounting ear 40 preferably perforated at 41. This ear is an integral part of a correspondingly longer median lamination 42 of the armature, which also has greater thickness for enhanced strength. In the common plane of the operating arm 38, and the lamination 42 said arm has a curved end or toe 43 which extends generally parallel but at a considerable distance from the end edge of ear 40. The armature and operating arm are rigidly connected together by a molded coupling 44, preferably of hard "Bakelite," which affords an intervening rigid solid insulating spacer 45 between the armature and the operating arm, and which embraces and embeds the toe 43 of the arm and embraces and also extends through the aperture 41 of the eye 40. Desirably, the molded connector 44 which extends in the common plane of lamination 42 and arm 38 is generally S-shaped to merge with the lengths of the armature A and the offset operating arm 38.

The movement of the operating arm 38 is resiliently opposed by a buffer, which in the particular embodiment disclosed where the arm oscillates back and forth in the plane of its width, desirably comprises an assembly including a pair of rectangular solid soft rubber blocks 46 interposed in the path of that movement. These blocks are carried by a retainer 47 best shown in Fig. 8, desirably of sheet metal, comprising a channel structure 48 provided with unitary lateral wings 50 and unitary end wings 51. The channel, lateral and end wings at each side are respectively engaged by the three faces that merge in one corner of the corresponding rubber block 46 which is thus supported as on a shelf. Unitary tongues 52 at the free end of the channel side 48' are turned out and block the longitudinal displacement of the rubber blocks. The retainer 47 has an aperture 49 in the middle for the operating arm 38. In the assembly, the rubber blocks 46 will engage the lateral walls of a corresponding well 53 in the casing. Desirably a further flat sheet metal retainer plate 54 is pressed against the inner faces of the rubber blocks 46 by the shoulder 55 formed at the free end of the insulating coupling 44. The operating arm 38 extends through central aperture 56 in plate 54.

The buffer assembly is securely retained in place between the operating arm 38 and the casing 10 without the possibility of displacement of the rubber buffers. The sheet metal retainer 47 serves to transmit the pressure from the lateral edges of the operating arm 38 through the widths of the resilient rubber blocks along the entire lengths thereof, so that the entire volume of the latter will effectively act as buffers and localized wear thereof will be guarded against.

Wire leads 57 and 58 for the electric motor are connected to terminals 59 and 60 near the rear end of the casing, which terminals protrude through a rubber block 61 therein molded as an integral part of the bushing 62 through which the conductor leads (not shown) extend. The leads 57 and 58 are desirably shielded against short circuit by an interposed sheet 63 of insulating material, such as Empire cloth, with a narrowed inner end that may be tucked as shown between the leaf spring 32 and the coil 34 and with its face tucked under the respective wire leads. The base of the bushing 62 is preferably embraced by corresponding registering notches 65 in the adjoining edges of the casing and its cover 10'. Desirably the rim of the casing extends obliquely upward to the full height of the casing at its forward or head carrying end as shown, and the cover has a complementary tapering flange conformation in edge to edge relation with the casing flange and terminating at a forward lip 66 in back of said head carrying end of the casing.

The magnetic circuit of the motor it will be seen, comprises a rectangular frame of relatively low reluctance, each of the lateral beams of which includes an air gap. The air gap 28 in the lateral beam of said frame nearest the rear of the casing is adjacent the thrust bearing 26, 27 and is within the corresponding electro-magnet coil 34, so that the magnetic leakage at said air gap is negligible. Since the electro-magnet coil 35 encloses air gap 33 the magnetic leakage thereat also is but small. Moreover since the effective air gap which is the distance between the two parallel oblique edges 22' and 24' of the respective legs 22 and 24 is considerably less than the length of armature stroke required to close such air gap, the power of the motor is substantially greater than it would be were the air gap at right angles with respect to the lengths of the corresponding legs of the field and armature structures.

Desirably the thrust bearing 26, 27 is not disposed symmetrically of the rear beam but is near the rear edge thereof as shown. The operation of the motor is thus rendered more uniform and smooth, since the movement of the armature leg 24 will be more nearly one of translation, than if its distance from the pivot 26, 27 were considerably shorter. Moreover the lateral movement of the operating arm 38 will be substantially one of translation, thereby compressing the rubber buffer blocks 46 substantially to uniform extent throughout the height thereof.

The armature A which is the sole moving element of the motor is under continual resilient restraint by the spring 32 at one end and the buffer assembly 46, 47 at the other end. The only engagement between relatively moving metal parts, aside from those of the shearing head, occurs at spring 32 upon anchoring projection 30 and at the thrust bearing 26, 27 of the motor where the movement is minute. The only other

relative movement of contacting parts is between operating arm 38 and buffer 46, 47 where such movement is completely taken up by the compression of rubber. The energy stored in spring 32 and buffer 46, 47 in the attraction of the floating armature A to the field structure F is given up on each change of phase of applied alternating current, to effect the return stroke of the armature. Impact in operation is thus wholly obviated, and wear and noise are kept at a minimum.

Desirably the rubber buffer 46 at the right in Fig. 1 is somewhat harder and more resistant than that at the left, so as to serve as a more or less positive buffer stop for the armature in its power stroke, thereby to preclude any possible closing up of the air gap 33 in that operation. The other buffer 46 is of relatively softer rubber to yield under the return stroke of the armature. The softer rubber buffer in effect causes the armature to bounce therefrom and thereby to give an effective start to the power stroke at the commencement thereof, where the air gap 33 is a maximum and the attractive power of the field coil a minimum. Desirably the two rubber buffers are distinguished from each other to preclude error in assembly by making the harder buffer of red rubber and the softer one of white. Of course, one or more shims (not shown) may be provided in association with the buffer structure to aid in the proper relative positioning of the magnetic parts in inactive position, so that the air gap shall be of the desired magnitude.

As many changes could be made in the above apparatus and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent is:

1. An apparatus of the character described, comprising a handle casing, a vibratory electric motor therein including an assembly of a fixed field structure and a vibratory armature, said assembly comprising a rectangular magnetic circuit with a pair of lateral bars having air gaps therein, the armature structure having a unitary projection at one of said bars with a direct rocking mount in a corresponding wider notch in the associated end of the field structure, field coils encircling said bars and said air gaps, means resiliently pressing upon the rear extremity of said armature and biasing the same away from the field structure, said armature having a unitary operating arm protruding through the front of the casing.

2. In apparatus of the character described, a handle casing, a vibratory electric motor therein including a generally U-shaped field structure having a base and two legs, a generally U-shaped armature structure having a base and two legs, the respective legs being in alignment to determine a generally rectangular frame, the end of one of said armature legs having a rocking thrust mount upon the corresponding leg of the field structure, the other pair of aligned legs of field and armature presenting an air gap therebetween, field coils encircling the respective pairs of aligned legs, said armature projecting rearward beyond said rocking mount, resilient means engaging the rear portion of said armature and

biasing the armature from the field structure, said armature having an operating arm protruding through the forward end of the casing.

3. Apparatus of the character described, comprising a casing, including a vibratory electric motor therein, made up of a field and armature assemblage including a fixed field structure having a pair of upstanding legs, an armature structure having legs in end to end relation with respect to those of said field structure, one of the legs of said armature structure having a ridge with direct thrust mount in a corresponding wider notch in the end of the field structure, the other pair of said aligned legs presenting an oblique air gap therebetween, said armature having an operating arm protruding through the forward end of said casing, and resilient means reacting against the rearward extremity of said armature beyond the pivot thereof for biasing said armature away from said field structure and a pair of coils about the respective pairs of aligned legs enclosing respectively the pivot and the oblique air gap.

4. In apparatus of the character described, a handle casing, an electric motor therein having a tool at the forward end of the casing, and a transmission arm intervening between said motor and said tool and a buffer structure yieldingly resisting the movement of said arm, said buffer structure comprising a sheet metal carrier mounted upon said arm and solid soft rubber means retained by said carrier and engaging the wall of the casing.

5. In an article of the character described, an insulating casing having a vibratory motor therein, including an armature having a pivot mount near the rear end of the casing and an operating arm protruding through the forward end of said casing, and buffer means coacting with a portion of said arm, resiliently to resist the movement thereof, said buffer means comprising a sheet metal carrier lodged in a corresponding well in said casing through which said arm extends, and solid rubber blocks mounted on said carrier at opposite sides of said arm and reacting against the opposite walls of said well to be alternately compressed and released in the vibratory movement of the arm.

6. In apparatus of the character described, an insulating casing, a vibratory motor therein including a field structure, an armature structure having a thrust bearing mount near the rear end of said casing, directly upon said field structure and including an operating arm protruding through the forward end of said casing, the width of said arm extending in the direction of oscillatory movement thereof, a sheet metal retainer having an aperture through which said arm extends, said retainer presenting lateral shelves, rubber blocks lodged on said shelves said retainer and blocks being retained in a corresponding well in the casing.

7. In apparatus of the character described, a vibratory electric motor having a field structure, an armature structure pivotally mounted upon one end thereof and including an operating arm at the opposite end thereof protruding through the forward end of the casing, said casing having a well through which the rear portion of the operating arm extends, a buffer structure for resiliently resisting the movement of said arm and lodged in said well, said structure comprising a pair of rubber blocks at opposite sides of the operating arm in the path of movement of the latter, and a sheet metal retainer and thrust

transmitter for said blocks, said retainer having angle-shaped holder portions at opposite sides thereof for engaging three faces of the respective blocks, a flat metal retainer plate engaging a fourth face of the two blocks, said arm extending through apertures in said retainer and retainer plate.

8. In an article of the character described, a casing, a motor therein having a vibratory armature with an operating arm protruding through the forward end of said casing, and a buffer structure through which said arm extends, said structure being lodged in a corresponding well in the casing, said structure comprising a sheet metal channel-shaped retainer with a pair of integral lateral wings and a pair of integral end wings, solid soft rubber blocks disposed laterally of said channel and pressing against the respective lateral and end wings, the outer lateral faces of said blocks coacting with the lateral walls of said well.

9. In an article of the character described a casing, a motor having a vibratory armature with an operating arm protruding through the forward end of said casing, and a buffer structure through which said arm extends, said structure being lodged in a corresponding well in the casing, said structure comprising a sheet metal channel-shaped retainer with a pair of integral lateral wings and a pair of integral end wings, solid soft rubber blocks disposed laterally of said channel and positioned against the respective lateral and end wings, the outer lateral faces of said blocks coacting with the lateral walls of said well, and upstanding wings integral with the side walls of said channel, turned over the ends of the rubber blocks, to hold the same against longitudinal displacement.

10. In an article of the character described, a casing, a motor having a vibratory armature with an operating arm protruding through the forward end of said casing, and a buffer structure lodged in a corresponding well in the casing, said structure comprising a sheet metal channel-shaped retainer with a pair of integral lateral wings and a pair of integral end wings, solid soft rubber blocks disposed laterally of said channel and positioned against the respective lateral and end wings, the outer lateral faces of said blocks coacting with the lateral walls of said well, a flat retainer plate and means pressing said plate against the faces of the rubber blocks, said operating arm extending through corresponding apertures in said buffer structure.

11. An apparatus of the character described, comprising an insulating casing, a vibratory electric motor in said casing, including a field structure, an armature structure having a pivot thrust mount thereon near the rear end thereof, said armature structure including an operating arm rigid therewith offset therefrom and protruding from the forward end of said casing, a buffer structure associated with the rear end of the said operating arm, said casing having a well accommodating said buffer structure, said buffer structure including a pair of solid rubber blocks lodged in said well at opposite sides of said arm, a sheet metal retainer carried by said arm and serving to transmit thrust from said arm in the movement thereof through the thickness of said buffer, along its entire length, an enlargement shoulder at the base of said arm and a retainer plate pressed by said shoulder against the faces of said rubber blocks.

12. In apparatus of the character described, 75

an insulating handle casing, a vibratory electric motor therein, comprising a field structure secured in the casing and having upstanding legs, an armature structure having downwardly extending legs in end to end relation with respect to those of the field structure, one of said pair of legs being in direct thrust bearing rocking engagement with each other, the other pair presenting an air gap therebetween, the rear ends of said field and armature structures having unitary anchor extensions, a leaf spring clasping said extensions and biasing the armature for opening the air gap, the armature structure including an operating arm protruding through the forward end of the casing, and buffer means intervening between said arm and the casing, resiliently to cushion the movement of said arm.

13. An apparatus of the character described, comprising an insulating casing a vibratory electric motor therein including a field structure secured to said casing, an armature structure in thrust relation therewith, a spring connecting the rear ends of said field and armature structures and biasing the armature for rocking away from the field structure, said armature having an associated operating arm protruding through the forward end of the casing and a rigid insulating connection between the forward end of the armature and the rear end of said arm, said connection comprising a molded body including a portion intervening between the respective ends of the armature and the arm and having end portions molded about the respective ends of said armature end arm, the operating arm being offset with respect to the armature to extend along the longitudinal axis of the casing and the arm having an upturned end extending generally in parallelism to the end of the armature and spaced therefrom and the molded connection extending in a general S curve for substantial continuity at its ends with the longitudinal portions of the armature and arm respectively.

14. In apparatus of the character described, an insulating casing an electric vibratory motor therein including a field structure securely mounted therein, an armature having a rocking thrust bearing mount near the rear end thereof with respect to said field structure, anchor extensions unitary with the respective arm and field structures at the rear ends thereof, a leaf spring connecting said two structures and biasing said armature away from said field, said armature structure including an arm protruding centrally through the forward end of said casing an insulating molded connector in the common plane of said armature and operating arm, rigidly connecting the forward end of the former to the rear end of the latter, a well in the casing about the rear portion of said arm, and a buffer assembly in said well including a pair of soft rubber blocks at opposite sides of the arm and sheet metal retainers therefor through which said arm extends, one of said retainers partially embracing the respective blocks and lodged in the bottom of the well, the other of said retainers being pressed by the end of said insulating connector against said rubber blocks.

15. An armature structure comprising a stack of thin magnetic laminations, a thicker lamination in the stack having an ear protruding from the forward end of said stack, a metal operating arm spaced from said ear and in the plane thereof, and a hard molded coupling embedding the

end of said operating arm and said ear and intervening between said two metal elements.

16. In an article of the character described, an insulating casing having a vibratory motor therein including an armature having a pivot mount near the rear end of the casing and an operating arm protruding through the forward end of said casing and buffer means coacting with a portion of said arm, said buffer means

including a pair of soft rubber blocks, one of relatively harder rubber to take the impact of the power stroke of the armature, the other at the opposite side of the armature and of relatively softer rubber to add a resilient impulse at the commencement of the power stroke of the armature.

JOHN A. HANLEY.
